UNITED STATES PATENT OFFICE.

ARTHUR TREVOR DAWSON AND GEORGE THOMAS BUCKHAM, OF WESTMINSTER,
LONDON, ENGLAND, ASSIGNORS TO VICKERS LIMITED, OF WESTMINSTER,
LONDON, ENGLAND.

MACHINE GUN.

Original application filed January 7, 1921, Serial No. 435,651. Divided and this application filed January 18, 1921. Serial No. 438,167.

(GRANTED UNDER THE PROVISIONS OF THE ACT OF MARCH 3, 1921, 41 STAT. L. 1313.)

To all whom it may concern:

Be it known that we, ARTHUR TREVOR DAWSON and GEORGE THOMAS BUCKHAM, both subjects of the King of Great Britain, 5 residing at Vickers House, Broadway, Westminster, in the county of London, England, have invented certain new and useful Improvements in or Relating to Machine Guns (for which we have made application in 10 Great Britain September 4, 1919, Pat. No. 165,858), of which the following is a specification.

This invention relates to machine guns of the Vickers automatic type and the application is a division of application Serial 15 No. 435,651. In such guns designed to have a relatively short recoil and to give a high rate of fire it is found, especially when the gun is of comparatively large calibre and is 20 firing a powerful cartridge, that the surplus or unabsorbed energy present at the end of the rearward movement of the parts on recoil is so great that when the usual curved surface on the forward part of the crank 25 handle at the side of the gun comes against the roller with which it co-operates the impact is so violent as to give rise to distortion of the mechanism casing or other parts of the gun; the chief object of the present invention 30 is to absorb the said surplus energy in such a manner as to obviate this disadvantage without reducing or materially reducing the high rate of fire for which the gun is designed.

According to the invention the crank is 35 provided with a part or surface adapted, at the end of the movement of the said crank during recoil of the barrel, to come against a fixed stop-piece (which preferably 40 forms part of or is attached to the usual filling piece at the rear end of the mechanism casing) the said part or surface and the said stop-piece being centrally arranged i. e. disposed equally on each side of a vertical plane 45 containing the axis of the barrel, so that the stresses resulting from the impact will be transmitted equally to each side-plate and will therefore not produce the aforesaid distorting effect.

In order that the said invention may be 50 clearly understood and readily carried into effect we will describe the same more fully

with reference to the accompanying drawings, in which—

Figures 1, 2 and 3 are respectively a side 55 elevation, a longitudinal vertical section and a plan (with the mechanism casing cover removed) of the rear portion of a Vickers automatic gun constructed in accordance with the present invention.

A is the mechanism casing, A^x is the crank, A' is the connecting rod pivoted at its rear end to the crank and at its forward end to the socket A⁰ of the side levers which are pivoted to the lock (the crank, the connecting rod and the side levers forming toggle levers as is well understood), A² is the 60 crank shaft, A³ is the crank handle and A⁴ is the roller with which this crank handle cooperates. B is the aforesaid stop-piece on 65 the filling piece B' at the rear end of the mechanism casing and C is the aforesaid part on the crank for coming against the stop-piece B at the end of the movement of the crank during recoil of the barrel. As 70 will be seen from Figure 3 the said part C and the stop-piece B are disposed equally on each side of a vertical plane containing the axis of the barrel as aforesaid, and are 75 preferably made of masses of high quality steel.

The invention is particularly intended for use with an automatic gun having one or more barrel-returning springs in addition to the fusee spring and is shown as employed 80 in conjunction with a gun of this character, D, D representing the said barrel-returning springs; in this case the crank handle A³ is 85 so constructed and arranged as not to come into contact with the roller A⁴ during the completion of the rearward movement of the handle, and for this purpose the crank handle is formed without the usual cam surface which is indicated by chain lines at a³ 90 in Figure 1. This roller is however still utilized for co-operating with the usual tail A^{3x} on the crank handle to break the toggle levers (constituted by the crank and the connecting rod) at the commencement of the recoil movement of the barrel as is well understood and in order to reduce the shock 95 resulting from impact between these parts we interpose between the roller A⁴ and its spindle or spigot A^{4x} a bush a of fiber or 100

other resilient material suitable for absorbing part of the shock.

What we claim and desire to secure by Letters Patent of the United States is:—

- 5 1. In a machine gun of the barrel recoiling type, the combination with a part recoiling with the barrel, a crank pivoted on said part, the lock, and a connecting rod connecting said crank to said lock, of a centrally arranged and rigid stop-piece, and a centrally arranged mass of metal on said crank, which mass strikes the stop-piece at the end of the movement of said crank during recoil of the barrel.
- 10 2. In a machine gun of the barrel recoiling type, the combination with a part recoiling with the barrel, a crank pivoted on said part, the lock, and a connecting rod connecting said crank to said lock, of a centrally arranged and rigid stop-piece, and a centrally arranged mass of metal on said crank, which mass strikes said stop-piece at the end of its movement during recoil of the barrel.
- 15 3. In a machine gun of the barrel recoiling type, the combination with a part recoiling with the barrel, a crank pivoted on said part, the lock, and a connecting rod connecting said crank to said lock, of a centrally arranged and rigid stop-piece, and a centrally arranged mass of metal on said crank, and projecting beyond the upper surface thereof, which mass strikes the stop-piece at the end of the movement of said crank during recoil of the barrel.
- 20 4. In a machine gun of the barrel recoiling type, the combination with a part recoiling with the barrel, a crank pivoted on said part, the lock, and a connecting rod connecting said crank to said lock, of a handle connected to said crank, a roller with which a tail on said handle co-operates at the commencement of the recoil movement of the barrel but which the handle is constructed to clear during the completion of its rearward movement, and a centrally arranged and rigid stop-piece, a centrally arranged mass of metal on said crank, which mass strikes said stop-piece at the end of its movement during recoil of the barrel.
- 25 5. In a machine gun of the barrel recoiling type, the combination with a part recoiling with the barrel, a crank pivoted on said part, the lock, and a connecting rod connecting said crank to said lock, of a handle connected to said crank, a roller with which a tail on said handle co-operates at the commencement of the recoil movement of the barrel, a spindle on which said roller is mounted and a bush, of resilient material interposed between said roller and said spindle.

ARTHUR TREVOR DAWSON.
GEORGE THOMAS BUCKHAM.
